UNITED STATES PATENT OFFICE.

JOHN T. HENTHORN, OF PROVIDENCE, RHODE ISLAND.

ROOF-COVERING.

SPECIFICATION forming part of Letters Patent No. 408,304, dated August 6, 1889.

Application filed February 25, 1889. Serial No. 301,154. (No model.)

To all whom it may concern:

Be it known that I, JOHN T. HENTHORN, a citizen of the United States, residing at Providence, in the county of Providence and State 5 of Rhode Island, have invented certain new and useful Improvements in Roof-Coverings; and I do hereby declare the following to be a full, clear, and exact description of the invention, such as will enable others skilled in the 10 art to which it appertains to make and use the same, reference being had to the accompanying drawings, and to letters of reference marked thereon, which form a part of this specification.

15 My invention relates to the covering of roofs, but more especially to "iron roofs," so called, used on fire-proof buildings. Roofs of this character are frequently used on the dynamo-houses of electric-lighting stations, factories, 20 engine-houses, &c.

A serious objection to a more general or extended use of metal-covered roofs is, I believe, due to the fact that the metal acts as a cooling-surface. In the sections of country exposed to wide variations in temperature as a 25 result of climatic conditions, particularly during the winter-season, the metal covering or roof directly exposed to the outer air acts to cool the air within the building, thereby reducing its humidity and causing the condensed moisture to collect on the under side of the roof, from which it drips to the floor below. Sometimes, in order to obviate the annoyance thus caused by the falling water, the 30 rafters have been covered with wooden plank or boarding, between which and the outer metal covering mill-board is interposed. While such construction may, in a great degree, prevent the collection of condensed 35 moisture it will not wholly do it, there being sufficient moisture produced upon the under side of the metal covering after awhile to permeate the interposed layer of paper and be absorbed into the wood, speedily causing it to decay. Another disadvantage to such wooden-lined roof is that it is not fire-proof from the 40 interior of the building.

The object I have in view is to produce a roof which is not only absolutely fire-proof both 45 from within and without, but at the same time one in which condensation is practically overcome.

To that end my invention consists, essentially, of a composite roof composed of an outer covering of metal, as corrugated iron, tin, 55 &c., and an inner covering of non-conducting incombustible material, as asbestos. Between these two may be interposed a layer or coating of tar, asphaltum, tar-paper, or other equivalent material adapted to prevent the water or moisture formed directly upon the under surface of the metallic covering from coming in contact with and saturating the asbestos lining, all as will be more fully hereinafter set forth and claimed. 60

65 In the appended drawings, Figure 1 is a perspective view of the upper portion of a building, showing a roof covered with corrugated iron according to my improvement. Fig. 2 is a transverse sectional view, enlarged, taken 70 through the roof; and Fig. 3 is a plan view.

75 My invention may be described more in detail, as follows: I would state that the drawings represent the roof as supported on iron rafters *u*. It is obvious, however, that wooden beams or rafters may be employed, although such use of wood would, in a measure, militate against the roof as regards its non-combustible qualities. As before stated, I prefer to use iron rafters, they being supported 80 by the walls of a building, as usual. To the rafters fore and aft metal purlins *p* are secured at proper intervals, also as common. The asbestos *b*, in the form of sheets more or less compressed, is supported by and in contact with the purlins. In order to render the asbestos sheets sufficiently strong, they may be lined with wire gauze or netting having a 85 comparatively fine mesh. In the drawings I have represented a backing *a*, formed of wire-netting, which covers the entire roof. The same rests upon and is secured to the purlins. The asbestos board *b*, of suitable thickness, is next placed upon the wire-netting. The drawings show two layers. When thus used, 90 the seams or joints of the upper course break joints with the course below. In order to render the roof perfectly impervious to moisture, I next cover the asbestos surface on top with one or more layers of tar-paper *e*, or other 95 equivalent material, followed by a mopping of hot tar *t*. A similar coating of hot tar may be applied to the first course of the covering *e*, if desired, as indicated by the drawings.

Finally, the outer covering *i* of metal is applied, and the whole securely fastened together at suitable intervals by bolts *m*, which also pass through the purlins, as clearly shown.

5 In engine-houses, dynamo-houses, &c., the metal covering *i* is usually made of corrugated iron, such form rendering the roof lighter, yet stronger and stiffer. An efficient joint is made by lapping the sheets along the edges so as to engage two or three corrugations.

I make no claim, broadly, to a metallic roof, or even to a corrugated-iron roof supported directly upon the purlins, the essential features of my invention being the interposition 15 of a surface of non-conducting incombustible material between the purlins or roof-supports and the outer metallic covering.

I claim as my invention —

1. A composite roof composed of an inner 20 lining or surface of non-conducting incombustible materials, of which asbestos forms the base thereof, purlins or other suitable supports therefor, and an outer covering of metal secured to said lining and purlins, substantially as described, and for the purpose specified.

25 2. A composite roof consisting of a corrugated-iron exterior surface, a surface of imper-

vious material, as tar-paper, contiguous to the under side of the corrugated iron, an asbestos lining upon which the said impervious surface rests, a surface of wire-netting to support the asbestos, and fixed purlins for supporting the whole, and to which the several surfaces or layers are secured, substantially as hereinbefore described.

3. The combination, with suitably-supported metallic purlins and an outer covering *i* of corrugated iron separated from said purlins, of a metallic netting *a*, resting directly upon 40 the purlins, a surface of asbestos board supported by the netting, and one or more layers of tar-protected impervious material laid upon the asbestos board, the whole arranged and secured together, substantially as described 45 and set forth.

4. A corrugated-iron roof having a lining composed of impervious material and asbestos resting upon a metallic base, substantially as described, and for the purpose specified. 50

In testimony whereof I have affixed my signature in presence of two witnesses.

JOHN T. HENTHORN.
